SHOE DISPLAY FORM

William L. Wardell, New York, N. Y., assignor to
United States Rubber Products, Inc., New York,
N. Y., a corporation of Delaware

Application March 10, 1937, Serial No. 130,089

4 Claims. (Cl. 12—128.1)

The present invention relates to shoe display forms, and more particularly to forms having reversible toe pieces, on which either a right or left shoe may be snugly fitted for display purposes.

5 Some types of shoes, such as bathing shoes and lounging slippers are soft, flexible, and easily deformable, due to the pliability, not only of their uppers, but of their soles, and often of their heel portions. For the attractive display of one of 10 these shoes, particularly a net or open-mesh bathing shoe, it is desirable to mount it on a form which will hold it in its proper shape, substantially as it will appear on the foot. It is especially important that the contour of the toe 15 portion of the display form should conform to the shape of the toe of the shoe, so that the true shape of the shoe will be retained and shown in an extended shape. Since the human foot is not bilaterally symmetrical, the toe portion of one 20 shoe form of the usual type will fit only the right or the left shoe, depending on which it is designed to fit. When a left shoe is mounted on a display form designed for the right foot, and vice versa, the toe of the shoe is distorted out of its 25 natural shape so that the display loses its attractiveness.

The present invention provides a form for displaying soft shoes which may be readily adjusted to accommodate either a right or a left shoe. 30 The form comprises two separable pieces, an upright heel-and-upper piece, and a toe piece fastened at right angles to the former. This toe piece may be removed from the upper piece, reversed, and replaced at will so that it will fit 35 either the right or left shoe.

The accompanying drawing illustrates a present preferred embodiment of the invention, in which:—

Fig. 1 is a side elevational view, partly in cross-section, along line 1—1 of Fig. 2, of the form;

Fig. 2 is a bottom plan view of the form when assembled to display the right shoe; and

Fig. 3 is a bottom plan view of the form when assembled to display a left shoe.

45 Referring to the drawing, a flat shank 1, of wood or other suitably stiff material is shaped, in side elevation, to simulate the general contour of a human foot and a portion of the ankle, in order to provide support for the heel and upper 50 of a shoe to be displayed. A notch 2 is provided in the lower forward edge of the shank to leave an overhanging portion 3 of the shank. A toe piece 4 is shaped like the toe of a shoe and has a slot 5 which is slightly narrower at edges 6 to- 55 ward the rear face of the toe element.

The toe piece 4 is attached perpendicularly to the shank 1, so that the slot 5 engages the lower edge 7 of the shank, the narrower edges 6 of the slot insuring a tight grip. The notch 2 fits the portion of the toe piece 4 in front of the slot 5, so that the overhanging portion 3 of the shank projects over and in contact with the toe piece, supplying the latter with added support from above to hold it in position. The toe element is easily removed, reversed, and replaced in chang- 10 ing from a right to a left shoe, or vice versa.

The shank 1 is of such shape that it suggests the heel and the greater part of the remainder of the foot. It also provides, by its ankle portion, a place to tie laces, an advantageous feature in the 15 case of open-mesh bathing shoes, which are often provided with laces. The toe piece 4, being securely attached to the shank, provides a natural contour for supporting the toe portion of a shoe. Fig. 2 illustrates the assembly when the obverse 20 face 8 is on the bottom ready to display a shoe for the right foot. Fig. 3 illustrates the same shoe form after the toe piece 4 has been removed, reversed, and refitted, the reverse face 9 appearing on the bottom. The shoe form is then as- 25 sembled to fit a left shoe.

The present invention provides a simple, efficient and attractive display form for shoes. It is inexpensive to manufacture. It is adaptable to fit either shoe of a pair. A shoe dealer who uses 30 exclusively shoe forms embodying the present invention will be prepared to display both shoes of a pair at the same time and will not be compelled to leave one on the shelf for lack of a form to fit it. The present display form may, of course, 35 be made up in whatever size is desired.

While a certain preferred embodiment of the present invention has been shown and described, it is to be understood that it may be otherwise embodied within the spirit of the invention and the scope of the appended claims.

Having thus described my invention, what I claim and desire to protect by Letters Patent, is:

1. A form for displaying a shoe, comprising a substantially flat shank having a notch along its lower front edge, and a toe-shaped flat toe piece fitted at right angles to said shank by means of a slightly rearwardly tapered narrowing slot adapted to receive the lower front portion of the shank, said toe piece being removable and re- 45

50 55 55
2. A form for displaying a shoe, comprising a flat upright shank having a notch along its front bottom edge, and a thin flat toe piece attached perpendicularly thereto having a slot with a nar-

- rowing taper toward its open end, said shank removably fitting into said slot so that the notch engages the toe piece at the slot opening.
3. A form for displaying a shoe, comprising a flat shank with a notch along the front bottom edge, and a thin flat toe piece disposed at right angles thereto having a slot narrowing toward the rear edge of the toe piece, said shank removably fitting into said slot so that the notch engages the toe piece in front of the slot opening, said toe piece being reversible to fit a shoe for either foot.
4. A form for displaying a shoe, comprising a

flat shank for supporting the upper portion of a shoe, said shank having a lateral surface corresponding substantially to the cross-section of a foot and ankle and having a notch along the lower forward edge, and a thin flat toe piece disposed at right angles thereto having a slot narrowing toward the rear edge of the toe piece, said shank removably fitting into said slot so that the notch engages the toe piece in front of the slot opening, said toe piece being reversible to fit a shoe for either foot.

WILLIAM L. WARDELL.
